(57) **CLAIM**

The ornamental design for an appliance handle, as shown and described.

DESCRIPTION

FIG. 1 is a front perspective view of a first embodiment of the appliance handle;

FIG. 2 is a front elevational view thereof;

FIG. 3 is a top plan view thereof;

FIG. 4 is a right side elevational view with the left side being a mirror image thereof;

FIG. 5 is a front perspective view of a Second embodiment of the appliance handle;

FIG. 6 is a front elevational view thereof;

FIG. 7 is a top plan view thereof;

FIG. 8 is a right side elevational view with the left side being a mirror image thereof;

FIG. 9 is a front perspective view of a Third embodiment of the appliance handle;

FIG. 10 is a front elevational view thereof;

FIG. 11 is a top plan view thereof;

FIG. 12 is a right side elevational view with the left side being a mirror image thereof;

FIG. 13 is a front perspective view of a Fourth embodiment of the appliance handle;

FIG. 14 is a front elevational view thereof;

FIG. 15 is a top plan view thereof; and,

FIG. 16 is right side elevational view with the left side being a mirror image thereof.

The broken lines illustrate environmental structure that forms no part of the claimed design.
